GARMENT DRYING CABINET

James H. Bequette, Sacramento, Calif., assignor, by direct and mesne assignments, of forty percent to Forrest J. McWilliams, Sacramento, twenty percent to John T. Cupples and twenty percent to Manuel L. Cervantes, both of Atwater, and twenty percent to Benjamin F. Davis, Sacramento, Calif.

Filed May 29, 1962, Ser. No. 70,344

Term of patent 14 years

(Cl. D49—1)

FIG. 1

FIG. 2

FIG. 3

The side not shown is substantially like the side shown.
I claim:

The ornamental design for a garment drying cabinet, as shown and described.
